UNITED STATES PATENT OFFICE.

JOHN J. KENNEY, OF PITTSBURGH, PENNSYLVANIA, ASSIGNOR TO THE BEST ELECTRIC COMPANY, OF PITTSBURGH, PENNSYLVANIA, A CORPORATION OF DELAWARE.

SWIVEL ATTACHMENT-PLUG.

1,290,229.

Specification of Letters Patent.

Patented Jan. 7, 1919.

Application filed April 25, 1917. Serial No. 164,512.

To all whom it may concern:

Be it known that I, JOHN J. KENNEY, a resident of Pittsburgh, in the county of Allegheny and State of Pennsylvania, have 5 invented a new and useful Improvement in Swivel Attachment-Plugs, of which the following is a specification.

The invention relates to swivel attachment plugs.

10 It relates more particularly to improvements in the novel form of attachment plug disclosed in the copending application of C. A. Vetter, Serial No. 19,361, filed April 5, 1915.

15 One of the objects of the present invention is to provide an improved swivel attachment plug of the general character set forth in the aforesaid application, in which a simplified form of electrical terminals are 20 employed; in which the terminals are more completely insulated from the rotatable screw shell; and one in which the screw shell is guided in its rotation and held in position in a novel manner.

25 Other objects and advantages of the invention will appear from the following specification.

An embodiment of the invention is illustrated in the accompanying drawings, the 30 views of which are as follows:—

Figure 1 is a cross sectional view of the parts making up the attachment plug, showing them in separated relation;

Fig. 2 is a cross section of the assembled 35 attachment plug;

Fig. 3 is a cross section at right angles to Fig. 2;

Fig. 4 is a cross section on the line 4—4 of Fig. 2;

40 Fig. 5 is a cross section of a modification of the plug shown in the first four figures; and

Fig. 6 is a cross section at right angles to the section shown in Fig. 5.

45 The attachment plug as a whole includes in general an insulating base 1 carrying projecting electrical terminals 2 and 3, a screw shell 4 mounted to rotate about the terminals in electrical engagement with one 50 of them, an insulating spacer 5, and a center contact 6 connected by a screw 7 to the other terminal for holding the parts together.

The general structure above described is similar to that disclosed in the copending

application referred to, but the present 55 structure includes a number of novel features which will appear from the following description.

The base 1 is made of any suitable insulating material, such as composition fiber, 60 hard rubber, porcelain, or the like. It is preferably made of a material that may be molded to shape, so that the electrical terminals may be molded in position at the time the base is made. An axial opening 8 65 extends through the center of the base to permit conductor cords to be passed therethrough, and in the present construction the top surface of the base has an annular projecting rib 9 which is of sufficient height to 70 act as a guide for the rotatable screw shell, as will hereinafter appear.

The electrical terminal 2 is carried by the base, and in the construction shown is embedded therein, it being held in position by 75 means of a bushing 10 having an irregular projecting end buried in the insulating material of the base. The free end of the terminal projects from the base preferably in line with the periphery of the opening therethrough and the extreme outer end is bent 80 over laterally, as shown in Figs. 1 and 2. The terminal carries a binder screw 11, the head of which engages the outer face of the terminal, and in order to enable a conductor 85 wire to be fastened beneath the binding screw, an opening 12 is provided through the terminal so that a wire may be threaded from the inside of the terminal through the opening and fixed around the binder screw, 90 as shown in Fig. 1. This enables the wire to be readily attached and at the same time the double-right-angle bend therein causes any withdrawal strains to be taken up largely by the terminal itself and the strain is relieved 95 from the point of attachment of the wire.

The terminal 3 is also carried by the base and embedded therein and it projects from the base approximately the same distance as the terminal 2. It also carries a binder 100 screw 13 and has an opening 14 for the passage of a conducting wire, the bottom edge of this opening being substantially the same distance from the base as the bottom edge of the opening 12 in terminal 2. The terminal 105 3 also has a lateral projection 15 which is adapted to be engaged by the rotatable screw shell, as will be hereinafter explained.

The rotatable screw shell 4 is of the usual type, its lower end being flanged around an insulating washer 16 which forms a gripping surface by means of which the shell may be rotated. The inside diameter of this washer is such that in flanging the shell around it an annular inwardly projecting rib is formed which fits around the annular rib 9 on the base so that the shell is rotatably guided by the coaction of the two ribs. The top of the rib in the screw shell forms a shoulder 17 which engages the projection 15 on the terminal 3 and thus completes an electrical connection between the shell and the terminal. The lower end of the shell adjacent the washer 16 is surrounded by an insulating ring 18 for preventing any portion of the shell 4 being exposed beyond the edge of the lamp socket in which the plug is inserted. The insulating spacer 5 is composed of any suitable insulating material, such as fiber composition, hard rubber or porcelain, and its outer end is preferably rounded to facilitate the insertion of the plug into a lamp socket. The spacer fits within the screw shell so as to permit the shell to be readily rotated and it is provided with two recesses 19 and 20 divided by an insulating wall 21 which, when the spacer is in position, extends between the terminals 2 and 3 and insulates them from each other. These recesses do not extend to the side exterior of the spacer but are separated therefrom by insulating webs or walls 22 and 23 which extend between the terminals 2 and 3 and the conducting portion of the rotatable screw shell, thereby completely insulating the terminals and the wires attached thereto from the shell. The bottom of the spacer is shaped to fit over the annular rib 9 on the base, as shown most clearly in Fig. 3, thereby preventing lateral movement of the base and spacer relative to each other and serving to position the spacer relative to the base. It will be noted that the lower end of the spacer does not quite touch the shoulder 17 on the screw shell but it projects a sufficient distance laterally to prevent removal of the shell as long as the spacer is in position. The shell may be freely rotated, however, with the annular rib thereon rotating in the annular recess formed between the spacer and the base. The side wall 23 has a recess 24 for the reception of the lateral projection 15 of terminal 3. The parts are held together in the construction shown by means of a screw 7 passing through the center contact 6 and engaging the bent-over end of the terminal 2. This screw electrically connects the terminal with the center contact and at the same time connects the spacer to the base which in turn holds the screw shell in place. This single means, therefore, forms a center contact and holds the parts together.

The construction described provides a swivel plug in which the terminals are thoroughly insulated from the screw shell and from each other by the insulating spacer, yet the terminals are readily accessible when the spacer and shell are removed. The spacer co-acts with a projection on the base to rigidly position the parts relative to one another and the rotatable screw shell is guided by an annular projecting rib on the base. The terminal 2 is of exceedingly simple construction, being merely an integral brass strip with its two ends bent at right angles. Nevertheless, this simple structure accomplishes the triple function of a terminal, a strain relief means and a means for engagement by the connecting screw for holding the parts together.

A modified form of the plug is shown in Figs. 5 and 6. The general structure of the parts is the same in this plug as in the one previously described and the same reference numerals have been used to describe similar parts. In this construction, however, the base 1, instead of being provided with a projecting rib, has an annular recess 25 formed in its upper face with which co-operates an annular projection 26 on the insulating spacer 5. The rotatable screw shell is guided in this construction by the projecting rib on the spacer, as will be readily understood by referring to the drawings. The base and spacer are positioned relative to one another by this structure and are also held in rigid relation.

It is to be understood that the structure shown is for purposes of illustration only and that other structures may be devised which come within the spirit and scope of the appended claims.

What is claimed is:—

1. A swivel attachment plug having an insulating base provided with an opening therethrough for the passage of conductor cords, electrical terminals carried by said base and projecting therefrom, a screw shell mounted to rotate about said terminals in electrical engagement with one of them, the other of said terminals having its outer end bent laterally, an insulating filler, and means passing through an opening in the filler and engaging the bent end of the second terminal to hold the parts together and form a center contact.

2. A swivel attachment plug comprising an insulating base provided with an opening for the passage of conductor cords, electrical terminals carried by said base and projecting therefrom, a screw shell mounted to rotate about said terminals in electrical engagement with one of them, the other terminal having a bent-over end, an insulating spacer adapted to be positioned in the screw shell to insulate the terminals from the shell and from each other, and means passing

- through an opening in the spacer connected to the bent-over end of the terminal to hold the parts together and form a center contact.
3. An attachment plug having an insulating base provided with an opening for the passage of conductor cords, electric terminals carried by said base and projecting therefrom, one of said terminals being provided with a bent-over end and the other 10 with a lateral projection, a rotatable screw shell adapted to rotatably engage the projection on one of the terminals, an insulating spacer having recesses in which the terminals lie whereby they are insulated from 15 the shell and from each other, and means passing through an opening in the spacer engaging the bent-over end of the terminal to bend the parts together and form a center contact.
- 20 4. A swivel attachment plug having an insulating base provided with an opening for the passage of conductor cords, electrical terminals carried by said base and projecting therefrom, said terminals having means for 25 attaching conductor wires to their outer faces and being provided with openings, the bottom surfaces of which are substantially equally distant from the base, whereby wires of equal length may be attached to the terminals and the terminals themselves relieve the strain from the point of attachment, a screw shell mounted to rotate about said terminals in electrical engagement with one of them, an insulating spacer adapted to insulate the 30 terminals and hold the rotatable screw shell in position, and means forming a center contact and passing through an opening in the spacer, one of said terminals having a bent-over end arranged to be engaged by said 35 means whereby the parts are held together.
5. A swivel attachment plug comprising an insulating base having an opening for the passage of conducting wires, electrical terminals carried by said base and projecting 40 substantially equal distances therefrom, one of said terminals having a bent-over end and both of the terminals being provided with means for attaching conducting wires to their outer faces and with openings, the bottom edges of which are substantially equi-distant from the base, whereby wires of 45 equal length may be attached to the terminals and the terminals themselves relieve the strain from the point of attachment, a screw shell mounted to rotate about said terminals in electrical engagement with one of them, an insulating spacer having recesses for the 50 reception of the terminals whereby they are insulated from the screw shell and from each other, and a center contact connected by means of a screw passing through an opening in the spacer to the bent-over end of the other terminal whereby the parts are held together.
- 55 6. An attachment plug having an insulat-

ing base provided with an opening for the passage of conducting wires, integral electrical terminals embedded in said base and projecting substantially equal distances therefrom, one of said terminals having a bent-over end and the other having a lateral projection struck up therefrom, both of said terminals carrying binder screws by means of which conductors may be attached to their outer faces and both terminals having openings therein, the bottom edges of which are substantially equal distances from the base whereby wires of equal length may be attached to the terminals and the terminals themselves form strain relief means, a rotatable screw shell having a shoulder adapted to rotatably engage the lateral projection on one of the terminals, an insulating spacer having recesses for receiving the terminals whereby they are insulated from the screw shell and from each other, said spacer being adapted to hold the screw shell rotatably in place, and a center contact connected by means of a connecting screw passing through an opening in the spacer to the bent-over end of the other terminal whereby the parts are held together and the center contact electrically connected to the other terminal.

7. An attachment plug having an insulating base provided with an opening for the passage of conducting wires, an annular projecting rib, electrical terminals carried by said base and projecting therefrom, a screw shell mounted to rotate about the terminals in electrical engagement with one of them and to be guided by the annular rib on the base, an insulating spacer arranged to be positioned within the screw shell to insulate the terminals and hold the screw shell in place, and means carried by the spacer electrically connected to the other terminal for holding the parts together and forming a center contact.

8. A swivel attachment plug having an insulating base provided with an opening for the passage of conductor wires and with an annular projecting rib, electrical terminals carried by said base and projecting therefrom, said terminals being arranged to form strain relief means for relieving the strain at the point of attachment of the conductor cords, a screw shell mounted to rotate about the terminals in electrical engagement with one of them and guided by the annular rib on the base, an insulating spacer adapted to be positioned within the screw shell to insulate the terminals and rotatably hold the screw shell in position, and means passing through an opening in the spacer and connected to the other terminal to hold the parts together and form a center contact.

9. A swivel attachment plug comprising an insulating base having an opening for the passage of conducting wires and an annular projecting rib, electrical terminals carried

by said base and projecting therefrom, one of said terminals having a bent-over end and the other having a lateral projection, and both of said terminals being arranged to 5 form strain relief means to relieve the strain at the point of attachment of the conducting wires, a screw shell mounted to rotate about the terminals in electrical engagement with the lateral projection on one of them and 10 guided by the annular rib on the base, an insulating spacer adapted to be positioned

within the screw shell to rotatably hold the shell in place, said spacer having recesses for the reception of the terminals whereby they are insulated from the screw shell and from 15 each other, and means passing through an opening in the spacer engaging the bent-over end of the other terminal for holding the parts together and forming a center contact.

In testimony whereof, I have hereunto set 20 my hand.

JOHN J. KENNEY.
